UNITED STATES PATENT OFFICE.

OTIS ANDREWS, OF EL PASO, TEXAS.

REFRIGERATOR SHIPPING-BOX.

SPECIFICATION forming part of Letters Patent No. 591,581, dated October 12, 1897.

Application filed October 23, 1896. Serial No. 809,794. (No model.)

To all whom it may concern:

Be it known that I, OTIS ANDREWS, a citizen of the United States, residing at El Paso, in the county of El Paso and State of Texas, 5 have invented a certain new and useful Improvement in Shipping-Boxes, of which the following is a specification.

My invention relates to a new and useful improvement in shipping-boxes for perishable goods, and has for its object to provide such a device in which oysters and the like may be shipped and at the same time their temperature kept at the desired degree without contaminating said oysters by direct contact 15 with the ice and the polluting of the natural juices by the water derived from the melting of the ice; and another object of my invention is to enable the box to be reused an indefinite number of times and also to reduce 20 the cost of shipping and increase the quality of the articles shipped therein when reaching their destination.

A further object of the invention is to produce a shipping-box in which oysters or other articles may be shipped without coming in direct contact with the ice and to reduce the melting of the ice to a minimum. These results are accomplished by providing a water-tight receptacle in which articles to be transported are placed. The receptacle itself is placed within a metal-lined box, after which ice is packed around the receptacle and the box is closed and secured for shipment. 30

In order that those skilled in the art to which this invention appertains may understand how to make and use the same, its construction and operation will now be described in detail, referring to the accompanying drawings, forming a part of this specification, in 35 which—

Figure 1 is a perspective view of a shipping-box made in accordance with my improvement, the top of the box as well as the lid of the receptacle being partly opened to illustrate their arrangement; Fig. 2, a longitudinal section of the box, and Fig. 3 a cross-section thereof.

In carrying out my invention as here embodied I provide a wooden box A, which is 40 of rectangular shape, and line the same with zinc, (indicated at B,) and to the bottom of the zinc lining is secured, by soldering or oth-

erwise, the clips C, adapted to receive the receptacle D, which latter is composed of galvanized iron or other suitable material and is 55 of rectangular shape, so that when placed within the box it will be held by clips against sidewise displacement, and when the top E of the box is closed upon the same the receptacle cannot move upwardly sufficiently to be 60 displaced from the clips. I prefer to form the top E with a reinforcement F, arranged to fit within the box when the top is closed, as clearly shown, in order that the box will be more securely sealed against the ingress 65 or egress of air.

The receptacle is provided with a cover G, hinged thereto at H by a continuous interlocking hinge, and is arranged to be secured in its closed position by the hasp I, adapted 70 to fit over the staple J, where it may be secured by a wire or other seal. A bead K is formed around the upper portion of the receptacle, and a spring-strip L is secured to the rear portion of the cover upon the under 75 side thereof, so that when the cover is closed the lower portion of this strip will bear against the inside of the receptacle just above the bead, thereby forming a tight joint which will prevent liquid contained within the receptacle from passing therefrom through the sections of the hinge. Strips M are also secured to the under side of the cover of the receptacle and project downward parallel with the flanges of this cover, so as to form a groove 80 85 into which the upper edge of the front and two ends of the receptacle fit when the cover is closed. This will form a tight joint between the cover and the receptacle at these points to insure the retaining of the liquid 90 contents of the receptacle.

In practice the oysters or other articles to be shipped are placed within the receptacle and the latter closed by its cover, after which blocks of ice are placed within the spaces between the sides of the receptacle and the box and between one end of the receptacle and one end of the box, and finally a sufficient quantity of cracked ice is placed within the space between the front of the receptacle 100 and the other end of the box in order to produce the same effect upon the contents of the receptacle without interfering with the hasp I and staple J, as will be readily understood.

When this has been accomplished, the top 5
E is closed and secured in place by the hasp
N, passing over the staple O, where it may be
secured by a lock. From this it will be seen
that the contents of the receptacle may be
shipped a considerable distance without be-
coming injured, since the ice contained within
the box and next said receptacle will keep
the contents thereof at the proper tempera-
ture until all of the ice has melted, and this,
on account of the box being securely closed
and no air being permitted to gain access
thereto, will last much longer than would
otherwise be the case.

15 In order to make the box more substantial
and enable it to resist harder usage, it may
be bound by strap-iron, (indicated at P,) and
for convenience in handling the box handles
Q are secured to the ends thereof.

20 Shipping-boxes made in accordance with
my improvement are especially adapted for
the transportation of all such articles as
crabs, shrimps, frog-legs, dressed turtle, fresh
lobsters, or fish of any kind, dressed poultry,
25 dressed meats, or any kind of perishable
goods without liability of deteriorating the
quality of the articles shipped by having the
ice come in contact therewith or the water
formed by the melting of the ice.

30 If found necessary, the grooves formed by
the strips M and the edges of the cover G
may have placed therein felt or other suitable
material, which will act as a packing for the

cover when closed, so as to further insure
the retention of the liquid contents of the 35
receptacle, as well as preventing water con-
tained within the box from gaining access to
the receptacle and its contents. Thus the re-
ceptacle may be opened and closed any num-
ber of times without decreasing its capacity 40
for retaining its contents, thereby enabling
the delivery of a portion of said contents and
the resealing of the receptacle, as well as the
reuse of the box, for further shipping pur-
poses.

45 Having thus fully described my invention,
what I claim as new and useful is—

In a device of the character described, a
wooden box lined with zinc, a cover for the
box, a reinforcement arranged on the cover 50
to fit within the box when closed, rectangular
clips secured on the bottom adapted to
receive a receptacle, a metallic receptacle
fitted within said clips, so as to leave a space
surrounding, a bead formed around the re- 55
ceptacle near the top, a cover spring-strips
secured to the top of the cover and adapted
to bear against the walls of the receptacle
above the bead, substantially as described.

In testimony whereof I have hereunto af- 60
fixed my signature in the presence of two sub-
scribing witnesses.

OTIS ANDREWS.
